EXAMPLE 2

290 g. (5 moles) of acetone and 73 g. (1 mole) of but-1-en-4-ol are heated for one hour at 270° C. in an autoclave, a pressure of about 250 atmospheres being set up. The reaction mixture is worked up by distillation; hept-1-en-6-one is obtained in a yield of 63% with reference to a conversion of 50%.

EXAMPLE 3

280 g. (3.2 moles) of diethyl ketone and 70 g. (0.8 mole) of 2-methylbut-1-en-4-ol are heated for forty-five minutes at 300° C., a pressure of about 250 atmospheres being set up. The reaction mixture is worked up by distillation; 2,5-dimethyloct-1-en-6-one is obtained in a yield of 48% with reference to a conversion of 39%.

We claim:

1. A process for the production of an alk-1-en-6-one which comprises reacting, at from 100° to 400° C., an alk-1-en-4-ol of the formula:

wherein each of the radicals R¹ to R⁵ when taken alone denotes a hydrogen atom or an aliphatic, cycloaliphatic or aromatic hydrocarbon radical having up to eight carbon atoms and wherein two of the radicals R¹ to R⁵ when taken together form a five- to seven-membered carbocyclic ring and wherein the alk-1-en-4-ol contains a total of from four to ten carbon atoms, with a ketone of the formula:

wherein each of the radicals R⁶ to R¹⁰ when taken alone denotes a hydrogen atom or an aliphatic or cycloaliphatic

hydrocarbon radical and wherein two of the radicals R⁶ to R¹⁰ when taken together form a five- to seven-membered carbocyclic ring and wherein the ketone contains a total of from three to eight carbon atoms.

5. A process as claimed in claim 1 wherein four of the radicals R¹ to R⁵ denote hydrogen atoms and the remaining radical denotes one of the said hydrocarbon radicals.

3. A process as claimed in claim 1 wherein but-1-en-4-ol or 2-methylbut-1-en-4-ol is used as the alk-1-en-4-ol.

4. A process as claimed in claim 1 carried out at from 200° to 350° C.

5. A process as claimed in claim 1 carried out at a pressure of up to about 1000 atmospheres.

6. A process as claimed in claim 1 wherein said ketone reactant is selected from the group consisting of diethyl ketone and acetone.

7. A process as claimed in claim 1 wherein the ketone reactant is acetone and the alkenol reactant is 2-methylbut-1-en-4-ol.

8. A process as claimed in claim 1 wherein the ketone reactant is acetone and the alkenol reactant is but-1-en-4-ol.

9. A process as claimed in claim 1 wherein the ketone reactant is diethyl ketone and the alkenol reactant is 2-methylbut-1-en-4-ol.
